DEVICE FOR CARRYING MAPS

Filed April 22, 1929

UNITED STATES PATENT OFFICE

GEORGE PERCIVAL KENT, OF GROVE PARK, LONDON, ENGLAND

DEVICE FOR CARRYING MAPS

Application filed April 22, 1929, Serial No. 357,128, and in Great Britain March 3, 1928.

This invention relates to and has for its object the provision of improvements in devices for carrying maps.

In accordance with the invention the device comprises a lens for affording observation of the map and means for adjusting said lens across the face of said map.

In order that the invention may be the more clearly understood a map carrier in accordance therewith will now be described reference being made to the accompanying drawings, wherein

Figure 1 is a face view of said map carrier and Figure 2 is a section on line 2—2 of Figure 1.

The numeral 1 designates say a road map of a town made of cardboard or the like. In front of this road map and spaced therefrom is a pane of glass 2 and spaced in front of this pane 2 and parallel therewith is a second pane of glass 3.

Pivoted at points *x* and *y* so as to be adapted to swing each in a plane parallel to and between said panes of glass 2 and 3 are respective extensible telescoping rods 4 and 5. The points *x* and *y* are above the map 1 and say vertically in line with the respective ends thereof. At their ends remote from said points *x* and *y* said rods 4 and 5 have handles 6 and 7 secured thereto by which said rods are adapted to be swung as stated. Said rods are adapted always to cross one another as shown.

Located between said panes of glass is a lens 8. This lens is of such a thickness as to form an easy fit between the panes and is located between the upper portions of the intersecting rods 4 and 5. Therefore when the structure is at its normal upright position shown, said lens 8 will rest in the upper angle between said rods 4 and 5 at a position determined by the angles to which said rods are set about their pivot points.

Around the two vertical edges and the lower edge of said map and in a plane just behind the pane of glass 2, a line of characters is marked as shown in Figure 1 said characters in the present example consisting of numerals starting from unity at the top of the left hand edge and running consecutively

to the top of the right hand edge. It will be seen that so long as the rods 4 and 5 support the lens over the map each rod will cross said line of characters and the position at which the two rods so cross said line will determine the position of said lens over said map. It may be found convenient to extend the line of numerals a short distance beyond the two extremities of the lower edge of the map as shown.

Supported at some convenient position are two frames 9 and 10 bearing a list in alphabetical order of the names of roads and/or other places shown on the map, each name has marked against it the two numerals at which the respective rods 4 and 5 will cross the line of numerals when said lens is over the corresponding place of the map.

When therefore it is desired to find the position of a given locality or street, the name of the same is looked up in the list and the two rods are set to angular positions at which they cross the line of numerals at the respective members indicated adjacent said name. An observation through said lens will then show an enlarged image of the portion of the map surrounding said street in which portion it is easy to pick out said place or street.

In construction the device comprises two frames 11 and 12 which are identical in face view and have rounded lower corners as shown. Said frames are secured together one in front of the other in spaced relation by means of spacing pieces 13 extending between the frame throughout the full length of the upper frame members and about half way down both side frame members as shown. The upper frame members of said frames 11 and 12 have longitudinal slots therethrough through which the glass panes 3 and 2 are slid into place and the side and bottom frame members are formed with grooves for the reception of the edges of said panes.

Secured completely around the edge of the structure constituted by said two frames is a strip 14 of sheet metal, said strip being secured in place after the panes of glass are located. This strip has a longitudinal slot therein at a position between the two frames which slot extends throughout all that por-

tion of the strip 14 which does not cover the spacing pieces 13.

The aforesaid handles 6 and 7 are stamped from sheet metal and have each two lugs 15 which project through this slot and a block 16 mounted at one side thereof which limits the movement of said handles into said slot. Slidably mounted on said lugs are washers 17 having convex surfaces presented to the metal strip 14 and urged by means of springs 18 against said strip. It will thus be seen that said lugs are slidable throughout the whole length of the slot in opposition to a force of friction determined by the force exerted by the springs 18. In practice this force of friction is sufficient to retain said handles at any position to which they are set. It will be clear that by virtue of the convex surfaces of the washers 17 said handles are enabled to turn easily round the curved lower corners of metal strip 14. Said handles 6 and 7 are also formed each with a lug 20 between said lugs 15 this lug is pivoted to the end of the respective rod 4 or 5 remote from the point *x* or *y*. The pivotal mounting of said rods 4 and 5 is effected by means of pins 21 mounted on the upper frame member of the frame 12 as shown in Figure 2. The map is mounted on a metal plate 22 removably secured over the back of the structure and the two frames 9 and 10 bearing the list of places are mounted on the structure by means of supporting arms 23 secured to this plate as shown. The list of places extends down both sides of each frame and said frames are pivotally mounted as indicated so that their faces may be reversed.

Located immediately behind the glass pane 2 and extending throughout the area thereof surrounding the map is a sheet of cardboard or the like 24 on which may be inscribed advertising matter. Spacing pieces 25 extend between this sheet 24 and the plate 22, which spacing pieces as will be seen also serve to frame the map.

It will be noted that in a map holder and indicator as hereinbefore described, the lens has a circular periphery and is free to move upwardly and downwardly, as well as crosswise, a support therefor being provided by the telescopic cross bars, and said telescopic cross bars not only serve as a lens support but also cooperate with the scale to indicate locality and movement of the telescopic bars positions the lens relative to the scale.

What I claim and desire to secure by Letters Patent is:—

1. A device for holding maps comprising a frame having parallel transparent sheets, a pair of telescopic cross bars maintained in pivotal and adjustable engagement with the frame to provide adjacent to their points of intersection a support for a lens.

2. A map holder of the character set forth comprising a frame, a pair of parallel trans-

parent plates and an offset back, a pair of bars pivoted to the frame and constructed to admit of longitudinal extension to serve as supports for a freely movable lens.

3. A map holder comprising a structure having a compartment formed by a pair of parallel transparent plates, a backing plate which is offset therefrom to constitute a map receiving chamber, a freely movable lens mounted between the transparent plates, and manually adjustable and extensible bars which provide a support for the lens, said bars being movable to position the lens both vertically and horizontally.

4. A map holder comprising a frame constructed to maintain a pair of spaced apart transparent sheets of material, and an opaque backing sheet associated with the frame and adapted to maintain a map, a scale on the inner face of the backing sheet, extensible bars pivoted to one of the sides of the frame, each of said bars being in adjustable engagement with the opposite side of the frame to admit of movement over the scale, and a lens supported by contact with the extensible bars adjacent to the intersection thereof.

5. In a map holder, a frame, a pair of spaced apart transparent sheets maintained by the frame and a backing plate spaced beyond the inner transparent sheet, a scale on the inner surface of the backing plate, a pair of telescopic bars which cross each other, one end of each of the bars being pivotally attached to the frame and the other ends being maintained in slidable engagement with side portions and the lower portions of the frame, and a lens which is adjustably supported by the cross bars.

6. A device of the character described comprising a frame which is constructively adapted to maintain parallel transparent sheets and a backing sheet, said frame having at its forward portion a longitudinal opening, a pair of telescopic bars pivotally secured to the frame, said telescopic bars at their opposite ends engaging adjusting means cooperating with the frame adjacent to its slots, and a circular lens which engages with the telescopic bars adjacent to their points of intersection.

In witness whereof I affix my signature.
GEORGE PERCIVAL KENT.
